Norman Bel Geddes, New York, N. Y.

Application December 4, 1934, Serial No. 755,865

6 Claims. (Cl. 114—0.5)

This invention relates to ships, and more particularly to an improved structure of ocean-going private yachts. Various matters may be conventional, as the submerged hull, which may be of so-called waveline type, or with a bilge keel for greater stability; the power plant oil-burning, preferably a low speed Diesel engine.

The present improvement refers to a novel and advantageous form of superstructure and to various cooperating features of ship construction, arrangement and operation; the general object being to improve the efficiency and utility of ships of the class referred to. A particular object is to improve seaworthiness as compared to conventional ships, namely by reconstruction of the superstructure form to minimize wind and water forces and afford stable smooth riding qualities, while securing maximum structural strength, and pleasing appearance.

20 A further object is to enhance the comfort of such a ship, for example by arranging for a maximum of uninterrupted deck spaces available in all kinds of weather and free of the various mechanical and equipment obstructions of the conventional yacht. While the ship hereof does not present the usual amount of permanently open deck space it affords ample open space, and additionally provides flexibly convertible observation and sun decks for fair weather use.

30 Another object of the invention is to effect a saving of fuel or increase of speed, namely by its novel form of superstructure, substantially reducing air resistance on streamline principles, therefore giving a greater speed and range of travel against head winds. Another object is to provide efficient and convenient means for accommodating and launching life or other boats. Various further objects and advantages will be hereinafter explained or will be apparent to those conversant with the subject.

40 The drawings as an example illustrate the structure of a steel yacht of proportions for about 8 passengers and crew of 30, with overall length 231.5 feet, beam 37, draft 12.5, displacement 45 1385 tons, driven by twin engines each of 1100 horse power, at a cruising speed of 16 knots per hour; the length to be relatively increased for higher speeds, and all dimensions varied to the demand.

50 Figure 1 is a perspective view of the complete vessel as seen from a point forward of the starboard beam.

Fig. 2 is a starboard side elevation.

Fig. 3 is a transverse vertical section on the line 3—3, and Fig. 4 at the line 4—4, of Figs. 55 2 or 6.

Fig. 5 is a longitudinal vertical central section.

Fig. 6 is a plan view at the navigation deck 60 level.

Fig. 7 is a plan view at the sun deck level.

Fig. 8, on an enlarged scale, is a top plan view of the forward observation deck with the outer top plates of the superstructure omitted to show the operating mechanism. Fig. 9 is a starboard 5 side elevation of the same showing the deck in its lowered position, and its raised or flush position in dotted lines. Fig. 10 is a front elevation of the same.

Fig. 11 is a top plan view of the convertible 10 sun deck on an enlarged scale. Fig. 12, on a still larger scale, is a sectional view taken on the transverse line 12—12 of Fig. 11. Fig. 13, on a yet larger scale, is like the lower part of Fig. 12 but showing the nested position of the sliding 15 panels when this deck is fully open.

Fig. 14 is a starboard side elevation showing the roof or shell plates above the after observation deck in open or uplifted position, the same shown closed in dotted lines. Fig. 15 is a top 20 plan view thereof. Fig. 16 is an after view of this deck and its convertible covering in closed position taken partly in section on the line 16—16 of Fig. 15.

Fig. 17 is a front elevation of the lifeboat 25 handling and launching mechanism, partly in section. Fig. 18 is a starboard side elevation thereof.

Fig. 19 is a front elevation, partly in section of the reception deck space at the social deck 30 level, the mechanism for operating its openable doors or platforms and the owner's launch handling mechanism. Fig. 20 is a starboard side elevation thereof.

Below the water line W. L. is the submerged 35 portion 20 of the ship's hull, its above-water portion 21 having a generally rounded bow 22 but with a forwardly curved prow 23, the after end of the hull tapering at 24 toward the stern. At the rear end of the keel 25 are the conventional 40 rudder and driving propellers. Fig. 3 indicates a bilge keel 25a.

The superstructure as will be more fully described comprises an enclosing shell which is generally exteriorly smooth and is of convexly 45 rounded form over its top and sides, the shell plates and the decks being supported on a conventional framework of longitudinals and laterals; the superstructure having its maximum transverse section well forward as shown, and 50 its after contour tapered toward the stern, and its protruding features generally harmonized in shape for low air resistance. The forward end 26 is preferably convexly rounded or domed so that the bow is generally blunt, and the long 55 tapered after end 27 terminates in a tail 28, all conforming generally with streamline principles.

For purposes of description the decks or levels from top to bottom will be termed: A, navigation deck; B, sun deck; C, social deck; D, state- 60

room deck; E, engine deck. Certain frame members are shown, longitudinals 29 and laterals 30.

Below the rounded bow end 26 is shown a flange-like outer deck or walk 31 in the nature 5 of a projecting rim, beneath which the prow 23 curves forwardly and merges into the extreme tip, acting to throw off impacting waves. This 10 deck or walk 31 may be of width to serve as exterior working space, and access thereto may be had at both sides by doors 32 leading from interior working and storage spaces, and of side to admit motor cars. At the stern projects an exterior 15 working deck or walk 33 of substantial width, to which the crew has access by doors 34 at the sides. The flange or rim decks 31 and 33 are shown at 20 deck levels B and C respectively, both of them at both sides extending well amidships.

The forward top deck is provided with a wave 25 breaker or shoulder 35 somewhat aft of the bow, to split and dispose of waves coming over the bow, and aft thereof is a second such shoulder 36, protecting the pilot house 38 from the wash.

The pilot house or bridge 38 is at the highest 30 point of the superstructure and well aft of the widest section; below its roof is a continuous window series 39 giving aspect in all directions. Following the pilot house is a tapered protrusion or curving hump 40 less wide but blending therewith and with the top deck form. These elements are 35 approximately amidships, affording a long substantially uninterrupted stream-line taper therefrom to the stern end and a clean outline to the forward end of the ship.

Adjacent these elements is a forward mast or 40 stack 42 which is hollow and constitutes an air intake, and well aft thereof is an after mast or stack 43 for air and gas discharge. Each of the stacks has regulable louvers 44. As masts they are available for lookout, radio and other purposes.

Substantially all other features of the ship are 45 enclosed or adapted to be enclosed, and the exterior structure constitutes an organized entirety, with necessary protrusions merged into the general outline, thus minimizing eddies and air resistance. At appropriate levels and positions are various square windows 46 and round port holes 47 and these are mounted to be flush with the skin or shell and weather-tight when closed. 50 By such structure maximum efficiency is afforded consistent with high comfort and utility. The skin constitutes an important strength element, its riveted or welded panels affording a truss structure reenforcing the interior frame, and 55 stiffening the ship longitudinally.

As an illustration of possible interior deck and space arrangements, at engine deck level E is the engine room 50, preferably two decks high, and at the same level are various tank and storage 60 spaces 51. At stateroom level deck D are three or more staterooms 52, crew's quarters and mess 53 and forward storage space 54 for anchor chain etc. At social deck level C, amidships is the large cross deck 55 openable to port and starboard, 65 adapted for reception purposes and for storing the owner's launch. Adjacent forward thereof is a living or reception room 56 and aft is a dining room 57. Forward of the living room is a library 58 and at the stern a large deck space 70 59 for the crew, connecting by the doors 34 already mentioned with the exterior deck 33. At sun deck level B may be officers' quarters 60, and further forward a garage space 61 and a crew work space 62 at the extreme bow connecting by 75 the large doors 32 with the exterior deck or walk

31. Aft of the officers' quarters is a large deck space 63 adapted to be opened to sun and air or closed tightly as will be described. To the rear thereof and aft of the exhaust stack or mast 43 is an openable and closable observation deck space 5 64. At the navigation deck level A is the pilot room 38 already mentioned, the roof of which forms a convenient outdoor space. Forward thereof is an observation space 65 which is normally flush but can be dropped to convert it for 10 use as an exposed deck, as will be described. Aft of the pilot house is a pair of rooms 66 auxiliary to the pilot room which may be used for storing charts, etc., and between these is an air intake chamber 67, fed by the hollow mast. Connecting stairways will be understood and various 15 other conventional features and auxiliary apparatus and facilities.

The air chamber 67 may feed to the engine room by a duct or inside stack 69, while an exhaust duct or stack 70 delivers spent gases to the after discharge mast. As between the hollow masts the intake and discharge may be reversed in some circumstances. Ventilating passages throughout the ship will be understood, and 20 conditioning apparatus, as well as blowers, fans and dampers to control the air.

The advantageous closed-shell or streamline type of ship described is subject to certain offsets raising practical problems in reference, for 25 example, to the provision of outer deckage for loading and other ship operations, and for health, recreation and reception purposes and enjoyment of the outlook, and in reference as well as to the need of accommodating and properly handling 30 life boats and service launch. These considerations are fully cared for with this invention, as will be described, commencing with the special exposed or convertible decks 63, 64 and 65, the forward and after overhung decks 31 and 33 having 35 been fully described.

The forward observation deck 65 is preferably 40 normally flush with the contour of the superstructure as in Fig. 2 but adapted to be dropped several feet as in Fig. 1 to constitute a pit or 45 well or sunken deck wherein the sun and air may be taken in security. It may be permanently at the lower level. Railings and awnings may be added. Access may be had from the interior by a hatchway at each side, comprising stairs 75 50 leading to the lowered deck level, see Figs. 8 to 10. A suspended door 76 is shown closing the passage from the deck to the stairway, and this door is hinged to a skin plate 77 which in turn is hinged to a fixed plate, so that at will the door 55 may be folded up against the plate and the latter may be thrown back or tilted up to give headroom, thus giving free access to the lowered deck. The drop deck is shown above the garage space, and when elevated fits tightly as a part of 60 the outer shell.

For lowering and elevating the drop deck 65 each corner has a projecting ear 79 having a threaded hole constituting a nut engaged upon a vertical screw 80, so that rotation of the four 65 screws lifts or lowers the deck. Each screw at its upper end has a worm wheel 81 driven by a worm 82 on a cross shaft 83. Each cross shaft carries a bevel gear 84 driven by a bevel gear 85 mounted on a vertical shaft 86. Each of the vertical 70 shafts 86 has a bevel gear 87 at its lower end and these engage bevel gears 88 on a lower longitudinal shaft 89, interconnecting the front and rear parts of the mechanism. To drive the system one of the vertical shafts 86 is extended 75

at 90 and carries a bevel gear 91 driven by a gear 92 on a cross shaft 93 having a worm wheel 94 driven by a worm 95 on the shaft of a motor 96, preferably electric and energized by conventional sources of current.

The sun deck 63 intended for recreation or relaxation purposes is rendered convertible by the provision of shell panels or plates which are removable from position preferably by telescoping or nesting so that this deck can be opened or closed at will. The covering over the sun deck comprises, along the center, fixed shell plates 100 which may be provided with glass windows 101, and the panels to be described might also consist of sashes containing glass, but are shown as simple metal plates. At each side the deck is partly enclosed by fixed shell sections 102 serving as rails, and the tops of these may be low enough to afford a view from the deck, or they and the mechanism within them might be located lower down to give an increased aspect. The deck space may be enclosed forward and aft by vertical cross walls 104.

The covering of the sun deck is shown as subdivided into five transverse rows of shiftable panels at each side, each two rows being separated by arched lateral frame members 30 sufficiently substantial to afford bracing strength in connection with the overhead longitudinal 29 and others. Near the top of each frame lateral 30, beneath the fixed top plates 100 is shown a fixed channel 105 at each side and from this point outwardly and downwardly extend the slidable curved panels 107, 108 and 109, three being shown in each row at each side. These panels may be guided by a system of projecting ribs 110 at each side of each lateral 30, supplemented by a system of guiding rollers 111, so that the several panels may be slid upwardly into their closed positions shown in Figs. 11 and 12 or downwardly into open position as shown in Fig. 13, where they are all accommodated within the rail or fixed side panel 102.

While the slidable panels 107, 108 and 109 might be moved in various ways, a convenient system is shown wherein the panels are interconnected with each other, so that the opening or closing movements may be effected by operation upon one only of the panels. Each upper panel 107 and second panel 108 is shown as having an inwardly extending flange 113 at its lower edge. The second panel 108 has an outward flange 114 at its upper edge engageable with the lower flange 113 of the first panel. A different coupling is provided between the second and third panels, the panel 108 having an eye 115 and the panel 109 a hook 116 engageable with the eye. By this arrangement when the first and second panels are slid up into closed position, the third panel may either be shifted with them, or if uncoupled allowed to remain in its lowered or open position, giving partial exposure to the sun deck. The lower edge of the third panel 109 has a wide outer flange 116 engaging, when closed, beneath an inner flange 118 on the rail plate 102.

Inward of the rail plate 102 is shown a fixed vertical housing wall 120 enclosing a space for the operating mechanism, and at the top of this wall 70 is a pivoted rail piece 121 which may be swung over to cover the enclosed space when the sun deck is fully or partly open, as in Fig. 13.

The sliding panels, preferably composed of stainless steel, are in overlapping relation and 75 arranged to shed water as far as possible, and

various usual packings, shields and the like are to be understood. When the sun deck is closed it is preferred that each of the panels, as it comes to its final position, engages upon a fixed incline or wedge operating to force it snugly against 5 the guiding ribs or tracks, thus rendering more tight the closed deck covering and preventing rattling.

The described convertible sun deck is quite flexible in its adjustments. The deck can be 10 opened or closed at either side, wholly or partly. The shifting mechanism may slide upwardly the respective panels 107, 108 and 109, at each row, to any desired extent, so that the covering may be opened near the top only, to a wide or narrow 15 degree, or the first or second panels can be pulled clear up after uncoupling the third panel, giving a wide overhead covering against rain but leaving the deck open by the width of one panel above the rail.

A convenient panel operating mechanism is that shown, comprising cables and means for guiding and pulling them to raise or lower the panels. For each row of panels at each side there may be the following. The top panel has 25 a depending bracket 123 to which is attached a cable 124 to pull the panel up and a cable 125 to pull it down. The cable 124 passes through the channel 105 and around a reversing pulley 126, and both cables overlie a series of small 30 pulleys 127 along the frame lateral 30. The two cables are thus brought within the housing 119, in which are guide pulleys 129 over which the cables pass on the way to the operating drum 130, on which the cables are oppositely wound. 35 Each drum is mounted loosely on a longitudinal operating shaft 131 turning in bearing brackets 132. Each of the several drums may be independently clutched to the shaft by means of a friction clutch 134 controlled from the deck by 40 a handle 135, so that when the handle is thrown the drum revolves, pulls one cable and pays out the other thus shifting the panels as desired, the friction slip in the clutch preventing breakage. The shaft 131 at a convenient point may be 45 driven by a reducing gear 137 rotated by a worm 138 on a shaft of a motor 139, which may be set in rotation in advance of any adjusting operation. By using a reversible motor it can first be started in the desired direction and the 50 clutches then operated to the extent desired.

The after observation deck 63, available as a semi-protected lounge deck is shown just aft of the mast 43, its floor being a portion of deck B and its roof being an adjustable portion of the outer shell between fixed shell portions 141 and 142, as shown in the general figures and in detail in Figs. 14, 15 and 16. The outer shell slopes downwardly at this point while the deck B is somewhat below the top fixed plate 142. The 60 convertible members comprise a central plate 143 of a triangular shape and hinged at its front edge to the fixed plate 141, its tapered rear end adapted normally to swing down flush with the fixed plate 142 or to be lifted sufficiently to open this deck to rear exposure. Hinged to each side of the central plate or panel 143 are wing panels 144, and these three panels are curved so as to conform and merge with the superstructure contour.

For rendering open the deck 63 there is shown a main lifting device or jack 146, conventionally illustrated as a hydraulic jack, located beneath the rear end of the center panel 143. Underneath the edge of each of the wings 144 is a rear jack 70 75

147 and a forward jack 148, which may be swivelled to allow for the lateral-swinging motion. The wing jacks may be enclosed within a housing or rail wall 150 at each side, conforming to the triangular deck shape.

5 In operation, water pressure may be opened to the main or central jack 146 by valve 152 and to the wing jacks at either or both sides, by valves 153, as desired. When all of the panels are 10 swung up to the open position shown a wide view is provided toward the rear and sides, while protected from the weather, and the upswung panels giving protection from gases issuing from the hollow mast 48.

15 The convex enclosing type of ship presents a problem in accommodating and launching life-boats from a high point, herein shown as at the navigation deck A. The position and general arrangement is indicated in the general figures, 20 Fig. 1 showing in dotted lines the open position of the parts and Figs. 5 and 6 indicating the location of the lifeboats; Figs. 17 and 18 showing the details of the launching mechanism at one side, the other side being similar.

25 The two lifeboats 156 are set longitudinally, each upon a dolly 157 upon deck A. The dollies have hinged chocks to reduce their height when out of use, and the dollies slide or roll transversely across the width of the ship at deck A 30 upon tracks 159, each having a locking lever 160 to secure the dolly in a given position. By this arrangement either lifeboat may be launched at either side since, after one boat has been launched, its dolly may be thrust clear to the 35 side, and the other dolly shifted into the position of the first.

The superstructure shell is normally closed, but for taking out the boat is adapted to be opened, for example as follows: A section or panel 162 of 40 the shell is hinged at its upper edge to constitute a door swingable from the full line to the dotted line position of Fig. 17. This door or panel is shown as having an interior lever 163 carrying a counter weight 164 sufficiently heavy to cause 45 automatic upswinging of the door when released.

The actual shifting of the lifeboat from in-board to outboard is effected by a pair of davit arms 166 swingable from the full line to the dotted line position of Fig. 17 about a fulcrum 50 167. These davit arms carry a substantial extent of shell 168 constituting a lower swinging panel or door. The boat compartment therefore is opened by the swinging up of the upper door 162 and the swinging out of the lower door 55 168, and when in position the door 162 may be confined in closed position by a latch 165, released when the davits are to be swung out. In addition to the door or panel 168 the davit arms 60 carry light plates 169 which, when the doors are closed, cover over and protect the shell recesses wherein the hinges 167 are accommodated.

The lifeboat 156 is shown as suspended from a pulley at the extremity of the davit arm by a lowering cable 170 which may be controlled 65 by the standard form of lowering tackle 171, unnecessary to describe. To swing the davits and boat from inboard to outboard position and vice versa, the middle parts of the respective davit arms are connected by long links or rods 70 172, each with a cross head 173 in the nature of a threaded nut fitted upon a long leadscrew 174 consisting of a threaded shaft turning in fixed bearings, so that by turning the screw the cross head is shifted progressively from one end to the 75 other and the link is thus operated to swing the

davit. This actuation may be effected by means of a bevel gear 176 on the screw shaft 174, said gear engaging a gear 177 on a transmitting shaft 178 which at its other end carries a bevel gear 179 driven by a bevel gear 180 on a longitudinal drive shaft 181 which operates the connections to both leadscrews. These connections are adapted to be operated either by hand or by motor, controlled from the lifeboat compartment.

10 In operation, the screw 174 is turned, the davit arms swing out, carrying the lower shell panel or door 168, which releases the upper door 162, the latter opens itself, the boat passes out-board to the dotted position above the water 15 and forward of the landing platform at deck C. The boat may be loaded inboard, or after being swung out, the deck panel 168 between the davit arms then forming a landing platform for entering the boat, which is then lowered clear of the 20 ship sides.

The owner's launch 184 is shown accommodated in the cross deck or reception space 55 at level C, at each side of which the shell plates constitute a door 185 swingable outward about 25 hinge or fulcrum 186 to constitute a landing platform; to which, when in use, may be attached a railing 187 and stairs and landing stage 188. Fig. 1 shows the door in receiving position, Figs. 2 and 3 show it closed and Figs. 30 18 and 19 show its operating mechanism and the boat handling mechanism in detail. For sheer strength the frame longitudinals 29 and laterals 30 surrounding the wide doorway are extra heavy; and if no launch is to be handled 35 lengthwise one or more lateral frame members could be retained vertically across the doorway, dividing it into sections.

When closed the door 185 is clamped weather-tight as follows: To an eye 190 at each end of the 40 door is attached by removable pin 191 a threaded bolt 192 engaged in a threaded bracket 193, and turned either way by a reversible ratchet and handle 194. When this device is loosened and uncoupled the door may be lowered by two 45 cables 196, detachable from the door, and operated by tackle 197. As later described each cable, at a certain stage, is slipped upon a pulley 198 at outboard position for the lowering of the door from horizontal to dropped position. Fig. 50 18 shows all three positions.

To allow door 185 to swing clear down its hinges 186 are shifted outboard, each hinge being mounted on carriage 200 slidably in a way 55 201 and having a rack 202 engaged by a pinion 203 turned by a removable crank 204. When in horizontal position, as a platform, the door may be there rigidly locked. For this, at two or more points are shown heavy bars 206, as I-beams, slidably partly into boxes or ways 207 in the 60 door, and retractable wholly inboard in ways 208 below the deck floor. The sliding of the lock bars may be manual as by poking them along by access through floor slots or otherwise.

The launch 184 may be handled as follows. 65 It is hung detachably from a light frame 211 by hook links 212. The frame is suspended by cables 213 from the arms 214 of davits 215, one near each end. Mounted on each davit is a hoisting winch 217, and each has its own motor 70 218. When stowed, the launch may be lowered upon chocks 219 on the deck floor, the chocks being collapsible and removable at will.

The two davits may be shifted laterally as follows. Each davit at its base has two wide 75

rollers 221 engaging on top of, and two pairs of narrow rollers 222 engaging underneath, the upper flange 223 of a long heavy cross beam 224. Each of these I-beams itself is shiftable across the deck to project outboard at either side at will. Its lower flange 225 rests upon a series of rollers 227 mounted below the deck level on angle irons 228. To steady the shiftable beam and prevent play when in its projecting position, shown in dotted lines in Fig. 18, there are pairs of hold-down rollers 227 mounted on angle irons 230 on the deck, these rollers bearing upon the top side of the lower flange 225.

The operation of the combined door and platform and the davit mechanism may be as follows. The door clamp devices 192 are released and the cables 196 attached to the door. The cables are paid out until the door projects horizontally, and the sliding bars 206 are thrust out to hold it rigid as a platform. If the boats is to be launched the carriages 200 are shifted to locate the hinges outboard. The large beams 224 are slid out to their dotted position Fig. 18, and the davits 215 are shifted to the extremities of the beams. The cables 196 are slackened and laid on the pulleys 198 at the beam ends and again tightened. The locking bars 206 are now retracted inboard, permitting the platform to be lowered to its depending position shown, thus clearing the way for the launching. The hoisting winch is operated to lower the frame 211 and boat 184 to the water, and the boat is unhooked from the frame. The platform may now be hoisted to and locked in horizontal position and the rails and landing steps attached.

A ship or yacht structure having thus been described as an illustration of the present invention, no limitation to specific features of construction, arrangement or operation is intended except as set forth in the respective claims.

I claim:

1. A sea-going yacht or ship whose superstructure comprises an enclosing shell containing a series of interior decks; and characterized by means as follows affording a closable landing platform; a side panel of said superstructure shell being formed as a door above the level of an interior landing deck, said door-panel having hinges at its lower edge thereby to swing out and down from closed to substantially horizontal open position flush with said landing deck where it serves as a landing platform, said panel having a transverse way formed therein, means to hold the door securely in closed position, and other means to hold it rigidly in horizontal position substantially flush with said interior deck, comprising an inboard way formed in said shell at the level of said deck and a rigid bar normally in said inboard way, said bar being normally disconnected from said platform but adapted to be shifted laterally partially outboard into locking engagement with the way of the platform, after the platform has swung down into horizontal position, thereby preventing up or down swinging thereof.

2. A sea-going yacht or ship whose superstructure comprises an enclosing shell containing a series of interior decks; and characterized by means as follows affording a closable landing platform; a side panel of said shell being formed as a door above the level of an interior deck, said door-panel having hinges at its lower edge there-

by to swing out and down from closed to substantially horizontal open position where it serves as a landing platform, means to hold the door securely either in closed or in horizontal position substantially flush with said interior deck, a carriage normally positioned inboard and carrying said door hinges, and means to shift outwardly such carriage and hinges to bring the hinges outboard and thus permit the door to be lowered swingingly into depending position.

3. A ship as in claim 2 and wherein an inboard way is formed in said shell at the level of said deck and the means holding the door rigidly in horizontal position comprising a rigid bar normally in said inboard way and adapted to be shifted partially outboard into locking engagement with the platform.

4. A sea-going yacht or ship whose superstructure comprises an enclosing shell containing a series of interior decks and having a side doorway above an interior deck; and characterized by means as follows for launching a small boat, a cooperative pair of heavy transverse beams mounted upon said deck for transverse sliding thereon, said beams being spaced apart further than the length of the small boat and carrying transverse trackways, and a davit-pair for a small boat located normally inboard and resting upon such trackways and slideable bodily thereon transversely of the deck, and spaced apart for the descent of the small boat between them, said beams, trackways and davits being located opposite to said doorway, whereby the beams may be slid outwardly partly through the doorway, and the davits may be slid outwardly on the beams, thereby to carry the small boat outboard for lowering between the spaced apart ends of the beams.

5. A sea-going ship with enclosed superstructure of generally rounded form constituting a shell and a system of interior decks, and with an interior lifeboat compartment above an upper deck whereat the deck width is substantially less than the greatest ship beam therebelow; and characterized by lifeboat launching means, comprising a normally enclosed pair of davit arms fulcrumed at their lower ends to swing outwardly to an extended position to carry a lifeboat outboard well beyond the greatest beam of the ship therebelow, clear of the ship sides, the shell having a doorway of ample length and height for the passage of the lifeboat and davit arms, a lower shell panel normally closing the lower part of the doorway and swingably mounted to swing outwardly and there constitute a boarding platform, and an upper shell panel normally closing the upper part of the doorway and retractible to clear the doorway for the passage of the lifeboat and davit arms; said lower panel or boarding platform being attached to swing outwardly and inwardly with said davit arms.

6. A ship as claimed in claim 4 and wherein said deck is provided with opposed exterior doorways, said pair of beams of a length of substantially the width of the deck located between said opposed doorways and shiftable outboard on either side, said davits movably positioned on said beams whereby a small boat may be moved to either side of the deck for launching through either of said doorways.
